UNITED STATES PATENT OFFICE

2,463,208

PAPER CURRENCY DISINFECTOR

Joseph J. Schutten, North Redondo, Calif.

Application August 5, 1947, Serial No. 766,140

5 Claims. (Cl. 21—76)

1

My invention relates to an apparatus for disinfecting paper currency and has for its principal object, to provide a simple, practical and inexpensive device designed for rapidly and effectively destroying contagious and infectious matter which may be carried by hand to hand circulated paper currency and which machine is particularly designed for use in banking institutions, hotels, public markets, general stores, theatres, ball parks, or wherever there is an exchange of substantial amounts of paper currency.

With the foregoing and other objects in view, my invention consists in certain novel features of construction and arrangement of parts which will be hereinafter more fully described and claimed and illustrated in the accompanying drawing, in which:

Fig. 1 is a side elevational view of my improved paper currency disinfector.

Fig. 2 is an enlarged cross section taken on the line 2—2 of Fig. 1.

Fig. 3 is an enlarged detail section taken on the line 3—3 of Fig. 2.

Fig. 4 is a fragmentary plan view showing the means for driving the endless flexible belt used in the machine.

Fig. 5 is a plan view similar to Fig. 4 and showing a modified form of the endless belt driving means.

Referring by numerals to the accompanying drawing, which illustrates a preferred embodiment of my invention, 10 designates a flat topped table or plate supported by legs 11, and mounted for rotation in bearings 12 on the ends of said table are the trunnions 13, of drums or rollers 14.

The upper flight of an endless belt-like member 15, traverses the flat upper surface of table 10, said belt being composed of one or more layers of fabric, more or less porous and preferably having a nap such as plush or velvet, so as to receive and hold finely pulverized disinfectant.

This belt is carried by the drums or rollers, 14 and to operate same, one of the trunnions 13 carries on its outer end a crank handle 16, as seen in Fig. 4, or a manually operable disc such as 17, seen in Fig. 5. Arms 18 are disposed alongside table 10, near one end thereof, and the ends of said arms adjacent the end of the table are pivoted to studs 18a on the sides of said table.

Transversely disposed on top of table 10 is a hollow roller 19 having a thin wall in which are formed perforations 20. One end of said roller is closed by a disc 21 having a trunnion 22 and

2

the other end is closed by a plug 23 having a trunnion 24.

Trunnions 22 and 24 are journalled in the free ends of arms 18 and retractile springs 25 connect the upper inner portions of arms 18, with the sides of table 10 near one end, thus maintaining roller 19 in yielding contact with the endless belt 15, or the paper currency carried thereby.

Trunnion 22, which is somewhat longer than 10 trunnion 24, carries near its outer end, inside arm 18, a loosely mounted disc 26, and positioned on said trunnion between disc 21 and disc 26, is a cylindrical plug 27, of sponge rubber. In some instances, an expansive spring may be used 15 in the place of rubber plug 27.

Perforated roller 19 contains a loose metal rod or roller 28 which, during rotation of said roller 19, rotates in the lower portion thereof, thus tending to provide a forcible feed of the pulverized disinfectant through aperture 20 in roller 19, and also functioning as a stirrer for the pulverized material.

In operation, the currency to be disinfected is laid flat on the endless belt 15 to either side of 25 roller 19 and by means of crank 16, the belt is driven so as to carry the currency beneath roller 19, and thus the disinfectant is simultaneously applied to both faces of the currency by said roller and belt. By driving belt 15 across the 30 table several times before beginning the disinfecting operations on a considerable number of bills, the loading of the belt with disinfecting material is insured.

In order to refill roller 19 with pulverized disinfectant from time to time, said roller is forcibly moved lengthwise toward elastic plug 27, thus compressing same and enabling trunnion 24 to be disengaged from its bearing in arm 18 and thereby permit the removal of plug 23.

40 Thus it will be seen that I have provided a paper currency disinfecting device that is simple in structure, inexpensive of manufacture and very effective in performing the functions for which it is intended.

45 Minor changes in the size, form and construction of the various parts of my improved paper currency disinfector may be made and substituted for those herein shown and described, without departing from the spirit of the invention, the scope of which is set forth in the appended claims.

While my improved device is particularly designed for use in disinfecting paper currency, it is to be understood that it may be employed with 55 equal advantage in disinfecting coins, tokens used

in business, playing cards, hat and coat room checks, in fact any relatively thin articles which are handled and rehandled by the public.

I claim as my invention:

1. In a paper currency disinfecter, a table, rolling supports on the ends of said table, an endless belt mounted on said rolling supports with its upper flight traversing the top of said table, a hollow perforated roller disposed transversely on the top surface of the upper flight of said belt, and means connecting said table and roller for causing the latter to exert yielding pressure against the upper surface of the top flight of said belt.

2. A paper currency disinfecter as set forth in claim 1, with a gravity member loosely arranged within said perforated roller.

3. A paper currency disinfecter, as set forth in claim 1, with a removable plug closing one end of said roller.

10

15

20

4. A paper currency disinfecter as set forth in claim 1, and means in support for permitting said roller to move bodily lengthwise of said supports.

5. In a paper currency disinfecter, an endless belt, a mounting therefor, a transversely disposed hollow roller mounted for rotation on the top flight portion of said belt and a gravity member arranged for rolling movement within said roller.

JOSEPH J. SCHUTTEN.
